UNITED STATES PATENT OFFICE

WILLIAM F. JOHNSON, OF UTICA, NEW YORK, ASSIGNEE OF ONE-HALF TO GEORGE J. ERVIN, OF UTICA, NEW YORK

GUARD ATTACHMENT FOR WRINGERS

Application filed December 8, 1930. Serial No. 590,783.

My invention relates to a guard attachment for wringers and I declare the following to be a full, clear, concise and exact description thereof, sufficient to enable anyone skilled in the art to which it appertains to make and use the same, reference being had to the accompanying drawings in which like reference characters refer to like parts throughout.

The object of the invention is to provide a device to facilitate feeding the wet clothes to the rollers of the wringer without the danger heretofore experienced of catching the fingers in said rollers.

Furthermore, the device is designed also to prevent that portion of clothes which has passed through the rollers from adhering to the same and returning thereon.

Moreover, the attachment is provided with demountable means for easily and quickly attaching it to a wringer.

The object will be understood by referring to the drawings, in which

Fig. 1 is a perspective view of the device.

Fig. 2 is a plan view showing parts broken away.

Fig. 3 is a side elevation of the device showing a portion of a wringer in dotted lines.

Referring more particularly to the drawings, the device embodies base plate 1 that is of suitable width to accommodate the clothes being fed to wringer 2 illustrated in dotted lines in Fig. 3.

A side member 4 is attached to each of the opposite sides of plate 1. Side member 4 is equipped with an upstanding bracket 5 having an aperture adapted to form a bearing for stationary shaft 6. Shaft 6 extends across plate 1 to bracket 5 on the opposite side. A flanged roller 10 is mounted to turn on shaft 6. An endless fabric belt 15 is run upon flanged roller 10 at one end, and at the other upon flanged roller 16. Roller 16 turns upon adjustable stationary shaft 17 that has bearings at opposite ends in the open slots 20, 20 made in upstanding members 21, 21.

The means for making shaft 17 adjustable embodies screw bolts 22, 22 which are screw mounted respectively to each of the upstand-

ing members 21, 21. The inner end of each of bolts 22, 22 projects into slot 20 and bears against member 24 which in turn bears against a coil spring 25 that is interposed between the corresponding end of shaft 17 and the end of bolt 22, whereby to allow shaft 17 to yield to a limited extent. Shoulders 30, 30 and raised portions 31, 31 of side members 4, 4 prevent the surplus water squeezed out of clothes from passing off the sides of plate 1. 55

Belt 15 is partially covered or bridged by hood 35 that is formed of three sides. The upper side 36 is supported sufficiently above the surface of belt 15 to allow for passage of the clothes therebeneath. Each of the lower edges of sides 37, 37 of hood 35 is bent over at right angles to form flat surfaces adapted to be riveted or otherwise fastened at 38, 38 to the upper surfaces of side members 4, 4. The rear edge of upper horizontal 70 side 36 is turned over at 40 to avoid a sharp edge at that location. The forward edge is extended at 41 and curved upwardly into a goose neck to supply a portion for the attachment of a rubber strip 42. The lower 75 edge of rubber strip 42 is free and adapted to make contact with the surface of rubber roller 45 of wringer 2 illustrated in fragment by dotted lines in Fig. 3, whereby to prevent clothes from winding backwards through the 80 wringer.

The means for securing the attachment to wringer 2 embodies depending brackets 47, 47 formed on the lower surface of plate 1. An aperture is made in each of the brackets 47, 47 for the reception of a bolt 50. Bolt 50 projects therebeyond through sleeve 51 of bracket 52. Its outer end is threaded for engagement with a tightening member 53. A handle 55 is mounted to member 53 to aid in turning the same. Each of brackets 52 is attached to wringer 42 by screws 60. Inasmuch as sleeves 51, 51 of brackets 52, 52 are disposed between the outer surfaces of depending brackets 47, 47 and the contiguous surfaces of members 53, 53, the turning of members 53, 53 by handles 55, 55, will pinch sleeves 51, 51 between said parts to hold the attachment at the proper angle to wringer 2. 95

In operation the clothes are placed upon 100

the endless belt 15 which is moved by its contact with the contiguous surfaces of revolving rollers 45, 45 of wringer 2 between which said rollers 45, 45 said belt 15 is disposed. The operator in feeding the clothes, not shown, to wringer 2 will be unable to catch his fingers between revolving rollers 45, 45 because of the intervention of the hooded guard 36.

10 Instead of using a tightening member 53 on the end of each of the bolts 50, it may be found desirable to employ a nut 56 on one of the bolts as illustrated in Fig. 2.

Having thus described my invention, what 15 I claim as new, and desire to secure by Letters Patent is as follows:

1. In a guard attachment for wringers, an endless belt, rollers for supporting said belt, one of said rollers being adjustable toward 20 and from the other, a guard member forming a hood for partially housing said belt, said guard member having an extension to prevent the clothes from returning on the wringer and means for adjusting said adjustable roller.

2. In a guard attachment for wringers, rollers for supporting an endless belt, one of said rollers mounted in open slots, bolts for moving said roller, whereby to adjust the 25 tension of said belt, a guard member forming a three sided hood for partially covering said belt, said guard member having a forwardly extending part with a rubber strip to prevent the clothes from returning through 35 the wringer and means for supporting said guard member in an adjustable manner with reference to said wringer.

In testimony whereof I have affixed my signature.

40 WILLIAM F. JOHNSON.
